CLAIM

The ornamental design for an absorbent article package, as shown and described.

DESCRIPTION

FIG. 1 is a front right perspective view of a first embodiment of an absorbent article package;

FIG. 2 is a front view thereof;

FIG. 3 is a back view thereof;

FIG. 4 is a right view thereof;

FIG. 5 is a left view thereof;

FIG. 6 is a top view thereof;

FIG. 7 is a bottom view thereof;

FIG. 8 is a front right perspective view of a second embodiment of an absorbent article package;

FIG. 9 is a front view thereof;

FIG. 10 is a back view thereof;

FIG. 11 is a right view thereof;

FIG. 12 is a left view thereof;

FIG. 13 is a top view thereof; and,

FIG. 14 is a bottom view thereof.

The broken lines are shown for the purpose of illustrating parts of the article that form no part of the claim. The shaded surfaces represent a contrast in appearance.

1 Claim, 10 Drawing Sheets
